UNITED STATES PATENT OFFICE.

LEE YOUNG DAVIS, OF ATLANTA, GEORGIA.

VENDING MACHINE.

Application filed August 13, 1920. Serial No. 403,336.

To all whom it may concern:

Be it known that I, LEE YOUNG DAVIS, citizen of the United States, residing at Atlanta, in the county of Fulton and State 5 of Georgia, have invented certain new and useful Improvements in Vending Machines; and I do hereby declare the following to be a full, clear, and exact description of the invention, such as will enable others skilled 10 in the art to which it appertains to make and use the same.

This invention relates to new and useful improvements in vending machines and more particularly to a device for vending liquids, 15 grains, and articles of a like character, the main object of the invention being the provision of a vending machine wherein certain quantities of liquid, grain or the like can be dispensed by the deposit of the required 20 amount of coins or tokens within the coin receiving mechanism.

Another object of the present invention is the provision of a vending machine, whereby the desired quantity of liquid, grain or 25 the like can be readily dispensed by depositing the requisite amount of coins or tokens in the proper coin actuating means, so that should a purchaser desire a quart of molasses, vinegar, or the like, he will deposit 30 a coin in the coin receiver adjacent the indicator, which will indicate that a quart of liquid can be obtained by depositing a coin within this slot.

A further object of the present invention 35 is the provision of a vending apparatus of the above character wherein the liquid or grain provided in the containers cannot be withdrawn without first depositing the required amount of coins or tokens to operate 40 the mechanism which will release the liquids or grain within the proper receptacles.

With the above and other objects in view, the invention consists in the novel features and construction, the combination and arrangement of parts, hereinafter more fully set forth, pointed out in the claims and shown in the accompanying drawings, in which—

Figure 1 is an elevation of a dispensing 50 device constructed in accordance with my invention, showing one of the receptacles in cross-section and in the operation of being filled,

Figure 2 is a vertical sectional view taken 55 on the line 2—2 of Figure 1, through one of

the receptacles, the lower valve member being open to release the contents thereof,

Figure 3 is a vertical sectional view taken on the line 3—3 of Figure 1,

Figure 4 is a transverse sectional view 60 taken on the line 4—4 of Figure 1,

Figure 5 is an elevation of a device for dispensing liquids, parts thereof being broken away and illustrated in section,

Figure 6 is a vertical sectional view taken 65 on the line 6—6 of Figure 5,

Figure 7 is a sectional view taken on the line 7—7 of Figure 5,

Figure 8 is a transverse sectional view 70 taken on the line 8—8 of Figure 5,

Figure 9 is a transverse sectional view taken on the line 9—9 of Figure 5;

Figure 10 is a diagrammatic view, illustrating several smaller containers or measures connected with the main receptacle, 75 whereby various quantities of material can be dispensed, and

Figure 11 is a diagrammatic view illustrating the smaller measuring vessels in connection with the main container and showing an indicator to indicate the fact that the main container has become empty.

In carrying out my invention, I provide a series of the receptacles upon the inside of the wall 1, each receptacle or measuring device being provided with individual coin receiving and actuating means and a plurality of the measuring receptacles are connected with a main receptacle such as illustrated in Figure 10. Each individual receptacle or measuring device includes a tubular body member 2, suitably secured to the inner face of the wall 1 by means of the outturned flanges 3, adapted to be secured to the wall 1 in any suitable manner.

These various measuring receptacles are connected to the main receptacle 4 by means of a plurality of conduits 5, leading from the main receptacle 4 to the various measuring receptacles as illustrated in the diagrammatic view in Figure 10. The measuring receptacles communicate directly with the conduits 5 so that the grain or other material will be readily conveyed from the main receptacle through the conduits 5 into the measuring receptacles 2. The flow of grain or other material is cut off from the receptacles 2 by means of the valve plate 6, which is mounted for swinging movement upon a pivot 7, said valve plate being provided with

a suitable opening 8, adapted to admit the grain or other material into the receptacles when the valve plate is in its open position. The valve plate 6 is normally retained in a closed position by means of the rod 9 which is connected to the coin expressor 10, the upper end of said rod being normally extended through an opening in the plate 6 to retain the plate in its closed position as illustrated in Figure 4.

The coin operating mechanism used in this form of the invention is arranged adjacent each one of the receptacles 2 and includes in its construction, the coin receiving member 11 provided with the vertically disposed slot 12 in which the coin expressor 10 is movable. The coin expressor is provided with suitable outwardly projecting arms 13 which are adapted to engage with the coin stop 14 to prevent downward movement of the coin expressor when an attempt has been made to move the expressor downwardly without first depositing the required coin or token within the coin receiver for releasing the grain or other material contained within the receptacle 2.

This control member or stop 14 provides a stop for the coin when the same is deposited within the chute 15. Thus, after a coin has been deposited within the chute 15, the same will move downwardly until it rests upon the stop 14, after which the expressor 10 is moved downwardly for engagement with the coin, the coin actuating the stop to permit the expressor to pass downwardly beyond the same, as illustrated in dotted lines in Figure 3. Upon downward movement of the coin expressor, the rod 9 will be moved downwardly so that the same will 40 become disengaged from the plate 6 and permit rotation of the plate so that the opening 8 can be thrown into alignment with the conduit which supplies the receptacle and thus filling the receptacle for dispensing the required amount of material.

After the expressor 10 has been moved downwardly to release the plate 6 and the plate 6 has been moved to an open position to permit the receptacle 2 to be filled, the rod 9 which has been previously forced downwardly at its lower end and engaged with the valve plate 16, is moved upwardly to disengage the rod 9 from the valve plate 16 and reengage the same with the plate 6 to retain the plate 6 in its closed position and permit the plate 16 to be opened to release the material which has been deposited within the receptacle 2. It will be noted that the wall 1 is provided with a slot 17 and the plate 6 is formed with a handle 18 adapted to operate within this slot 17, whereby the plate 6 can be readily actuated by the purchaser from the exterior of the wall 1.

The coin expressor 10 is operated through the medium of a rod 19, which extends down-

wardly through a guide sleeve 20 and is provided with an arm 21 which extends transversely and is connected with the coin expressor at a point adjacent the rod 9. The upper end of the rod 19 is provided with a finger plate 22, which can be readily grasped by the operator to force downwardly upon the rod 19 and actuate the coin expressor 10. Each of the valve plates 6 and 16 are provided with suitable coil springs 23 to normally retain the valve plates 6 and 16 in their closed position, thus after one of the plates has been moved to an open position to permit the material to pass therethrough, the handle of the plate is released, the tension of the coil spring returning the plate to its normal closed position.

The pivot pins upon which the plates 6 and 16 are mounted are supported by means of the brackets 24, which are riveted or otherwise secured to the sides of the receptacles 2, so that when the plates are mounted upon these pins, they will be in a position to readily swing between the various sections of the receptacles so as to cut off communication between the same. In Figure 1, it will be noted that the plate 6 is disposed between the upper end of the main receptacle and the conduit leading therein so that when the plate is in its closed position, as illustrated in Figure 4, the contents of the conduit cannot drop downwardly into the receptacle. It will also be noted that the lower end of the rod 9 is provided with a suitable guide sleeve 25, whereby to guide the same through the opening in the lower plate 16 when it is desired to lock this plate in its closed position, while the receptacle 2 is being filled.

In the general operation of my improved device for dispensing grain and material of like character, a coin is first deposited within the chute 15, said coin gravitating downwardly under the stop 14 and in order to release the plate 6, so that the opening 8 therein can be moved into alignment with the receptacle 2 and the conduit 5, the coin expressor 10 is moved downwardly within the slot 12 engaging the coin to force the same beyond the stop 14, this movement will carry the rod 9 downwardly until the upper end thereof is disengaged from the plate 6, permitting the plate 6 to be swung to an open position by means of the handle member 18, so that the material from the conduit 5 will readily flow into the receptacle 2. After the receptacle 2 has been filled, the rod 19 which has been previously forced downwardly to actuate the coin expressor 10, will be returned to its normal position by means of the coil spring 26, which is disposed between the finger plate 22 and the shelf portion 27, this movement will draw the rod 9 upwardly to release the lower end of the same from the plate 16 and again engage the same with the

plate 6 to retain the plate 6 in a closed position and permit the plate 16 to be opened. It will be noted that the plate 16 can be readily operated from the outside of the wall 1 by means of a handle member 28 which extends through the front face of the wall to a position whereby it is readily accessible to the operator. Thus, it will be noted that the plate 16 can be swung to an open position to permit the material from the receptacle 2 to be drawn off into any desired container. Communicating with the lower end of the receptacle 2 is the spout 29 which extends outwardly through the wall 1 so that the purchaser can readily obtain the material contained within the receptacle 2, which has been released by depositing the requisite amount of coins or tokens within the coin receiver.

20 It will be noted that as each of the plates 6 and 16 is released, the coil springs 23 will return the plates 6 and 16 to their normal closed position, as illustrated upon the left hand side of Figure 1. These coil springs 23 are connected at one end to a pin 30 which is attached to the wall 1, while the other end of the spring is connected to the plate 6 at the inner edge thereof.

25 In Figures 5 to 9, inclusive, and in Figure 11, I have illustrated the form of the invention particularly adapted for dispensing materials in liquid form, the operation of the coin mechanism and the means for releasing the dispensing valves being substantially 30 the same as that disclosed in the Figures 1 to 4, inclusive. In this form of the invention, the receptacles 2' are provided with offset portions at each end having vertically disposed sleeves 31, in which are mounted the 35 valve members 32 and 33, the valve 33 being arranged at the connection between the receptacle 2' and the inlet pipe 34 which communicates with the main supply pipe 35. The valve member 32 is provided with a 40 stem 36 having extended therefrom a plate 37 provided with a perforation to receive the upper end of the rod 9' to retain the valve member 32 in its closed position until a coin has been inserted within the coin 45 chute 15' and the expressor 10' moved downwardly to release the rod 9' from the perforation within the arm 37. This operation will release the valve 32 and permit the same to be rotated by means of a handle 50 member 38, secured to the stem 36 and projecting through a suitable slot 39 in the wall 1', whereby this handle member can be readily grasped by the purchaser for admitting the material from the supply pipe 34 into 55 the receptacle 2'.

60 After the receptacle 2' has been filled, the coin expressor is returned upwardly to its normal position, illustrated in Figure 6, thus releasing the lower end of the rod 9' from the perforation in the arm 40, which is se-

cured to the valve stem 4' of the lower valve 33. This operation will permit the lower valve 33 to be operated by means of a handle member 42, so as to open communication between the receptacle 2' and the nozzle 43, 70 which is connected with the sleeves 31 and extends outwardly through the wall 1' through the opening 39 thereof, so that the purchaser can readily obtain the contents of the receptacle 2' by operating the handle 75 42 to open the valve 33.

75 It will be noted in Figures 8 and 9 that I have disclosed the specific type of valve to be used, which is preferably a two-way valve as illustrated, so that when the arms 80 37 and 40 are locked by means of the rod 9', these valve members will be in the positions illustrated in Figures 8 and 9, so that no liquid or other material can pass therethrough. In order to return the valve members 32 and 33 to their locked positions, I provide suitable coil springs 44, having one of their ends attached to a perforated lug 85 45 on the valve stem and the other end attached to a suitable bracket 46, formed on the side of the receptacle 2' in the case of the lower valve member 33, while the coil spring 44 has one of its ends attached to a bracket 47, secured to the inner face of the wall 1.

90 In Figure 11, I have illustrated a diagrammatic view, including a main supply tank 48, having communication with an indicating receptacle 49, which will indicate to the attendant that only a certain amount 95 of liquid or other material is contained within the tank 48, so that the supply in the tank 48 can be replenished before the entire amount has been drawn out.

100 In the operation of my improved device, 105 for dispensing liquid materials, a coin is first deposited within the chute 15', the coin gravitating downwardly to the stop member 14', the finger plate 22' is then engaged by the fingers or hand of the operator to force downwardly upon the rod 19', which will actuate the coin expressor 10', forcing the same downwardly within the groove 12' to engage the coin and force both the coin and the coin expressor beyond the stop 14', this operation releasing the arm 37 of the 110 valve 32, so that the purchaser can readily grasp the handle member 38 and open the valve 32 to permit the material from the supply pipe 34 to pass into the container 2'. After the container 2' has been filled, the valve 32 is closed and the rod 19' moved upwardly again to its normal position, illustrated in Figure 6, to disengage the rod 9' from the arm 40, to release the valve 33, the upper end of the rod 9' again engaging the 115 arm 37 of the valve 32 to retain this valve in its closed position until another coin has been inserted within the chute 15'. The valve 33 having been released, the purchaser grasps the handle 40 and rotates the 120 125 130

valve member to open communication between the receptacle 2' and the delivery spout 43, whereby the contents of the receptacle 2' can be readily drawn therefrom.

5 From the above description, taken in connection with the accompanying drawings, it will be readily apparent that I have provided a dispensing device, wherein the contents of the main receptacle cannot be drawn therefrom without first depositing the required amount of coins or tokens in the proper slots provided therefor and only the actual amount of material can be drawn from the container 2' by depositing the 10 requisite amount of coins or tokens in the chute 15'.

What I claim is:

1. In a vending device the combination of 20 a receptacle having inlet and outlet ports, valves controlling said ports, valve control members for said valves rotatable in parallel spaced planes, a rod reciprocable intermediate said valve control parts and adapted to engage said parts respectively at opposite ends of its stroke.

2. In a vending device the combination of 25 a receptacle having inlet and outlet ports, valves controlling said ports, a pivoted control member for each of the valves, the pivots for said control members being in substan-

tial alignment and a rod reciprocable between said control members and of a length adapted to disengage one of said parts when it engages the other.

3. In a vending device the combination of 35 a receptacle having inlet and outlet ports, valves controlling said ports, pivoted control members for said valves adapted to operate in parallel spaced planes, said control members formed to receive a latch, a reciprocal latch rod operable between the control members and of a length to disengage one when it engages the other of said members.

4. In a vending device the combination 45 of a receptacle having inlet and outlet ports, valves controlling said ports, a pivoted valve control member for each valve, said control members operable in parallel spaced planes, spring means associated with said members to normally close the valves, a latch rod reciprocable between said control members adapted to disengage one when it engages the other, and spring means operable on said latch rod to keep it normally 50 in locking engagement with the inlet valves control member.

In testimony whereof I affix my signature.

LEE YOUNG DAVIS.
